(57) **CLAIM**

We claim the ornamental design for a vehicle frame, as shown and described.

DESCRIPTION

FIG. 1 is a top, front, right perspective view of a vehicle frame showing our new design;

FIG. 2 is a front elevational view thereof;

FIG. 3 is a rear elevational view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top, front, left perspective view.

The broken lines in the drawings illustrate portions of the vehicle frame which form no part of the claimed design.

1 Claim, 6 Drawing Sheets
